NECKTIE RACK

Alfred Köhler, Brooklyn, N. Y.

Application February 15, 1937, Serial No. 125,774

1 Claim. (Cl. 211—99)

This invention relates to racks for the disposal of neckties of the lengthy, four-in-hand type and of miscellaneous flexible articles.

Wearers of ties usually have an assortment from 5 which to select in accordance with the occasion and season, as fashion and custom may dictate.

An assorted collection of ties disposed haphazardly in a case, drawer or the like, soon become creased and out of shape, presenting a worn, 10 dilapidated appearance, annoying to a well dressed person.

While it is known, that wire racks are available, the small diameter of the supporting wires produces a sharp bend in the ties. They are further objectionable because of the difficulty in 15 properly adjusting the ties on them, and furthermore require considerable space for the disposal of a large assortment of ties.

Having these matters in mind, it is an object 20 of the present invention to produce a tie rack, which avoids the mentioned disadvantages, while fulfilling its purpose in an efficient manner.

A further feature is in the provision of a rack 25 having rungs of such diameter, as to avoid sharp bends in the tie body, and to arrange the rack so, that ties may be easily displayed thereon and readily removed.

Another purpose is to produce a rack adapted 30 to occupy a minimum of space, ordinarily unused, and which may be held horizontally extending or hang normally in a pendant position.

These and other meritorious objects such as 35 economical construction, pleasing appearance and practical use are accomplished by the novel, construction and combination of few and simple parts, hereinafter described and illustrated in the accompanying drawing, constituting a material component of this disclosure, and in which:

Figure 1 is a perspective view of an embodiment 40 of the invention, showing its application.

Figure 2 is a top plan view, partially in section, of the device, drawn to an enlarged scale.

Referring in greater detail to the drawing, the

numeral 5 designates in general a conventional door, having panels 6 set between the sides, and cross-pieces 7 of the door.

Attached to one of the upper cross pieces are the flanges 8 and 9 of spring brackets 10 and 11, 5 the latter having a circular depression 12 in its inner face.

A pair of bars 15, preferably wooden, shown as oblong rectangles, are connected at widely spaced intervals by a plurality of smooth-surfaced 10 wooden rungs 16 of circular cross-section and of considerable diameter, on which the ties are to repose, as indicated in Figure 1.

The upper ends of the bars 15 are engaged by clamp screws 17 passing through appropriate 15 openings in the brackets 10 and 11, and disposed intermediate the inner faces of the brackets and adjacent surfaces of the bars are friction washers 18, one of which is adapted to engage in the depression 12 sufficiently to retain the rack when 20 extended horizontally, as seen in the broken lines in Figure 1, thereby greatly facilitating the disposal and removal of a selected tie from the rack.

Although the foregoing is descriptive of the best known embodiment of the tie rack, it is 25 apparent that minor changes could be made in its construction without departing from the scope and substance of the claim hereto appended.

Having thus described the invention and set 30 for the manner of its construction and use, what is claimed as new and sought to secure by Letters Patent, is:

In a tie rack, a pair of spaced straight flat bars having large diameter tie supporting rungs secured therebetween, a pair of wall-attached 35 spring brackets each having a fixed flange, at least one of said brackets having a depression in its inner face, pivot screws carried by said brackets and engaging said bars, and a friction washer on the screw carried by the bracket having 40 said depression, said washer being engageable in the bracket depression.

ALFRED KÖHLER.
